OPEN HOLE SLEEVE PACKER

Mordica O. Johnston and Thomas A. Andrew,
Glendale, and Adelbert M. Graham and Walter
G. L. Smith, Los Angeles, Calif.

Application June 18, 1941, Serial No. 398,624

2 Claims. (Cl. 186—10)

This invention relates to oil well tools, and particularly pertains to an open hole sleeve packer.

In oil well operations where it is desired to pack off the well at a particular point, it has been common to use a sleeve type packer which is expanded into the well bore or casing and forms a seal therewith. Various types of packers have been employed in this manner including multiple ring packers and sleeves which represent an entire cylindrical packer wall of a desired length. Due to the simplicity of operation and relative cheapness of this last named type of packer its use is desirable. It has been found, however, that in using a deformable sleeve packer in an open hole that due to the irregularities in the walls of the well bore the longitudinal compression of the packer will deform and expand it and will cause the packer to expand unduly in the less confined areas of the well bore, thus tending to permanently stretch and deform certain parts of the packer, and at the same time making it necessary to increase the length of the packer to get a proper seal. When the length of the packer sleeve is increased under the conditions specified, it is found that the rate of expansion in various sections of the packer proceeds at a rate in excess of that existing at other points, and that when excessively stretched or expanded the rubber does not have sufficient strength to limit this expansion and will transfer the force to other points so that expansion throughout the length of the sleeve will be at a substantially uniform magnitude. In fact, the impression has been given to some observers that in some cases where abnormal expansion starts at any particular point it accelerates, comparatively speaking, rather than decelerates, imparting to the packer a corrugated outer surface as represented by portions of the packer which have expanded more than others, with the result that the packer operates ineffectively and after a small amount of use may lose its usefulness. It is the principal object of the present invention, therefore, to provide a packer of the sleeve type which, while relatively small in diameter, may be expanded due to longitudinal compression to a much greater expanded diameter than is now the case, while the expansion longitudinally of the packer is uniformly controlled to prevent inequality in expansion action at given sections of the packer, thereby insuring a maximum sealing action and a minimum amount of destructive wear.

The present invention contemplates the construction of a sleeve packer having a wall of deformable material, such for example as rubber,

and within which a helical strengthening and equalizing element is incorporated to control and distribute compressive and expansive forces in the structure.

The invention is illustrated by way of example in the accompanying drawing, in which:

Figure 1 is a view in elevation showing the application of the present invention.

Fig. 2 is an enlarged view in vertical section showing the packer construction.

Fig. 3 is a view in transverse section as seen on the line 3—3 of Fig. 2 showing the packer construction and its reinforcing and equalizing element.

Referring more particularly to the drawing, 10 indicates a sub having a box 11 at its upper end to receive a supporting string of pipe 12 and a pin 13 at its lower end to connect with a tubular extension 14. The lower end of the tubular extension is internally threaded and receives an upper pressure element 15 of the packer structure generally indicated at 16. A lower pressure element 17 is disposed at the lower end of the packer structure and is fitted with a pin 18 which is threaded into an anchor pipe 19. The upper pressure element 15 is formed with an upwardly projected threaded extension 20 which engages the tubular extension 14. The pressure element 15 is formed with a central bore 21 extending longitudinally therethrough. The diameter of the bore 21 is less than the inside diameter of bore 22 extending through the tubular extension 14, with the result that an upwardly presented shoulder 23 is formed on the member 20 and within the bore 22. Resting normally on this shoulder is a stop nut 24 carried by a tubular mandrel 25 onto the upper end of which the nut is threaded. This mandrel extends downwardly and its lower end is threaded at 26 to engage a complementary threaded portion in the lower pressure element 17. A circulation passageway 21 is formed through the lower circulation element and completes fluid circulation from the tubular mandrel. Interposed between the upper pressure element 15 and the lower pressure element 17 is a cylindrical sleeve 28 which is made of deformable material such as rubber and constitutes the packer sleeve. This sleeve has a wall of a thickness as represented by the distance from the outside diameter of the tubular mandrel 25 to the outside diameter of the pressure elements 15 and 17. Incorporated within the mass of the material forming the packer wall 28 is a helical spring element 29 which serves the purpose of reinforcing the packer and distributing and controlling the compression and expansive

action of the packer walls when longitudinal compression is exerted upon the packer element by relative movement of the pressure elements 15 and 17 toward each other.

As seen in Fig. 2 of the drawing the diameter of the convolutions of the element 29 is such as to dispose the helical member substantially in the middle of the mass of material forming the wall of the packer sleeve 28. Imbedded in the opposite ends of the sleeve 28 are cylindrical thimbles 30 and 31 which are formed of suitable material, such as brass, and have an annular groove 32 in their outer circumference and into which the ends of the helical element 29 are fitted and thereafter held in place by brazing or the like. Thus, the helical member will be fastened by its opposite ends to the thimbles, which in turn are imbedded within the packer sleeve. At the outer ends of the thimbles an annular shoulder 33 is formed. Fitting around this shoulder and also into grooves 34 formed around the circumference of the pressure elements 15 and 17 are split fastening rings 35. These rings are channel shape in cross-section and are held in position by screws 36. The split rings act to embrace the ends of the pressure elements 15 and 17 contiguous to the packing sleeve 28 and to embrace the ends of the packing sleeve, thus reinforcing and protecting the same and positively securing the packer sleeve to the pressure elements 15 and 17. By this arrangement the square ends of the thimbles 30 and 31 rest directly against the square ends of the pressure elements 15 and 17 so that longitudinal force is applied directly to the thimbles and then to the packer sleeve 28. The tubular mandrel is guided within the upper pressure element 15 by a suitable bushing 37. The bushing 37 is fixed upon the tubular mandrel and moves therewith. Extending transversely through the tubular mandrel and the upper end of the bushing and also into the upper pressure element 15 is a shear pin 38. This pin acts to hold the upper pressure element 15 in fixed relation to the lower pressure element 17 without imposing compression upon the packer sleeve 28 until it is desired to set the sleeve.

In operation of the present invention the structure is assembled as shown and lowered into the well until the anchor pipe 19 strikes the bottom of the well. Sufficient weight is then applied to the drill string 12, the sub 10, the tubular extension 14, and the upper pressure element 15 to shear the shear pin 38. Further downward force exerted by the aforementioned elements will impose a longitudinal compression strain upon the packing sleeve 28 and compress the same while deforming it in a lateral direction. The rubber which occurs between the convolutions of the helical element 29 and the tubular mandrel will be compressed and forced outwardly between the convolutions of the element 29 and against the wall of the well bore. There will therefore be a tendency to distribute the compression force and control the deformation of the packer uniformly throughout the length of the packer. It will be seen that if at any single convolution of the reinforcing element 29 there is a greater expansive stress than at some other point in the length of the sleeve, pressure will be set up in the mass of rubber adjacent to that point in excess of that present in any adjoining convolution and will confine the rubber so that further compression will not take place. This insures that the rubber in the area between the 75

reinforcing helix 29 and the tubular mandrel will reach approximately the same pressure throughout, and that the expansive movement of the material due to longitudinal compression will be equalized throughout the length of the packer sleeve 28 and uniformly therearound. It will further be noted that the reinforcing helix 29 will tend to limit the amount of expansion to which the sleeve can be forced, and will also act to contract and restore the packer to its original form. It has also been found that due to the strength given by the helix 29 the ability of the rubber to maintain its form and properly embrace the tubular mandrel throughout a compression and de-compression cycle is greatly increased, and that a larger amount of expansion of the rubber sleeve can be obtained without danger. This last named feature makes it possible for the packer sleeve to be of a smaller diameter than usual, thereby increasing the flow space between the packer and the wall of the well bore to facilitate in lowering the packer into the well. When the packer is inserted and set and when it is being withdrawn from the well it will be noted that the weight of the string of pipe below the packer will place the helical element 29 under tension and will tend to contract the packer, since the helical member which is imbedded within the packing sleeve will be contracted. This is due to the fact that both ends of the helical element are fixed. The upper end is fixed with relation to the upper pressure element 15 and the lower end with relation to the lower pressure element 17. By this arrangement it is insured that the packer will be contracted as it is unseated so that the packer may be withdrawn easily without unduly abrading or tearing it.

It will thus be seen that by the structure here shown a suitable sleeve type packer of any desired length may be obtained to pack off difficult formations and to operate efficiently with long life.

While we have shown the preferred form of our invention as now known to us, it will be understood that various changes may be made in combination, construction, and arrangement of parts by those skilled in the art, without departing from the spirit of our invention as claimed.

Having thus described our invention, what we claim and desire to secure by Letters Patent is:

1. A sleeve-type well packer, comprising a tubular mandrel, a lower pressure element fixed thereon, an upper tubular pressure element telescopically connected with the mandrel, interengaging means retaining the mandrel and upper tubular pressure element in telescopic connection, a tubular deformable packer sleeve mounted on the mandrel between the pressure elements and positively secured by its ends to said elements, and helical reinforcing means imbedded within and extending longitudinally of the sleeve and permitting longitudinal compression of the sleeve between said pressure elements while restraining expansion of the packer sleeve at intervals in the length of the sleeve, said helical means being likewise positively secured by its ends to said pressure elements.

2. A sleeve-type well packer, comprising a tubular mandrel, a lower pressure element fixed thereon, an upper tubular pressure element telescopically connected with the mandrel, interengaging means retaining the mandrel and upper tubular pressure element in telescopic connection, a tubular deformable packer sleeve mounted on the mandrel between the pressure elements

and being positively secured by its ends to said elements, a helical reinforcing member imbedded within and extending longitudinally of the sleeve and permitting longitudinal compression of the sleeve between said pressure elements while restraining expansion of the packer sleeve at intervals in the area of the sleeve within which the helical member is directly imbedded, the ends of said helical member being positively secured

to the upper and lower pressure elements, and means temporarily holding the mandrel and the upper tubular pressure element against relative longitudinal movement.
